(57) **CLAIM**

The ornamental design for a toolbox for a gooseneck trailer, as shown and described.

DESCRIPTION

FIG. 1 is a front perspective view of a toolbox for a gooseneck trailer;

FIG. 2 is a larger presentation of the toolbox for a gooseneck trailer shown in FIG. 1;

FIG. 3 is a front elevation view of the toolbox for a gooseneck trailer;

FIG. 4 is a rear elevation view of the toolbox for a gooseneck trailer;

FIG. 5 is a left-side elevation view of the toolbox for a gooseneck trailer;

FIG. 6 is a right-side elevation view of the toolbox for a gooseneck trailer;

FIG. 7 is a top view of the toolbox for a gooseneck trailer;

FIG. 8 is a bottom view of the toolbox for a gooseneck trailer; and

FIG. 9 is a front section view of the toolbox taken along section 9-9 shown in FIG. 5;

FIG. 10 a front perspective view of a toolbox for the gooseneck trailer of FIG. 1, wherein a roll-up door is illustrated in a partially open position; and,

FIG. 11 is a front section view of the toolbox taken along section 11-11 shown in FIG. 10.

The broken lines shown in FIGS. 1 through 11 depict environmental subject matter and portions of the toolbox for a gooseneck trailer that form no part of the claimed design.

1 Claim, 11 Drawing Sheets
